UNITED STATES PATENT OFFICE.

HENRY E. HALLBORG, OF WASHINGTON, DISTRICT OF COLUMBIA.

RADIO SIGNALING SYSTEM.

Application filed July 24, 1923. Serial No. 653,493.

My invention relates broadly to radio transmission circuits, and more particularly to a transmitting circuit utilizing the arc or like generator of sustained oscillations.

5 One of the objects of my invention is to provide a signaling circuit which eliminates the compensation wave ordinarily radiated by a high power arc transmitter.

Another object of the invention is to provide 10 a circuit arrangement for an arc or like generator whereby only the fundamental working wave frequency is radiated by the antenna system and mush and harmonics eliminated.

15 Another object of the invention is to provide a coupled circuit arrangement whereby the generator is inductively connected with the antenna system instead of being directly in the antenna circuit as heretofore employed.

20 A still further object of the invention is to provide a keying system for uniwave signaling capable of high speed operation wherein steady operation of the generator 25 is insured during signaling with substantially no fluctuation of power in the generator circuit during signaling.

25 My invention will be more fully understood by reference to the accompanying drawings, in which:

Figure 1 is an elemental diagram representing a coupled arc transmitting circuit and the connections of the signaling keys in the primary oscillating circuit and in 30 shunt with the primary coupling coil; Fig. 2 is a diagram of an arc transmitting circuit wherein the signaling keys are placed in the primary oscillating circuit and in shunt with the secondary coupling coil; Fig. 3 shows a modified circuit arrangement with 35 means for changing the reactance between the primary oscillating circuit and the antenna circuit when keying to a sufficient amount to prevent leakage of energy from 40 the primary oscillating circuit into the antenna circuit when it is desired that it should be excluded therefrom whereby the antenna circuit is less likely to have any residual current therein during space intervals between 45 signals; Fig. 4 shows the application of my double by-pass circuits connected with an arc transmitting circuit functioning with the coupled circuits for suppressing the 50 radiation of harmonics from the antenna system; and Fig. 5 is a chart showing observations taken with a receiver on different wave

lengths within a short distance of an arc transmitting station showing the freedom of the system from harmonics.

The necessity for single wave signaling 60 with high power arc or like generator circuits has become increasingly apparent with the increase in the number of signaling stations and the recognition of the limited number of bands of frequencies available for 65 transmission. The importance of suppressing interference from harmonics which are usually radiated by such systems has also become apparent with the large increase in the number of listening in stations which 70 have followed the installation of broadcast stations.

In my present invention I provide a coupled arc or like generator circuit which eliminates mush and harmonics, and to further exclude harmonics I provide by-pass 75 circuits in the primary coupled circuit having high reactances for the fundamental frequency and low reactance for harmonic frequencies. In transmitting the signals a 80 key is placed in shunt with the primary coupling coil or the secondary coupling coil, and a key is also placed in the primary oscillating circuit in shunt with an absorbing circuit and the keys alternately operated to 85 produce the signal. No fine adjustment to insure overlap condition is necessary as is the case in keying other types of circuits.

Referring more particularly to the drawings, Fig. 1 shows one arrangement for keying the coupled circuit. Reference character 1 represents the direct current power circuit which supplies the arc 2. The arc is provided with an arc field 3, which may be either self or separately excited. The field 95 is preferably separately excited in order to take full advantage of the reduction in mush and harmonics by the medium of the loose coupled circuit hereinafter described and the accurate adjustment of the arc transverse field strength. Reference characters 4 and 5 represent respectively the capacity and inductance of the primary circuit, capacity 4 being so selected as to cause the arc 2 to work at relatively high supply 100 voltage where its efficiency as a converter is the greatest. Reference character 6 denotes the primary of the antenna coupling coils coupled with the secondary 7 connected in the antenna circuit. The antenna circuit 105 comprises antenna 8, antenna loading coil 9, radiation ammeter 10, and ground or

counterpoise 11. The primary coupling coil 6 is shunted by a short circuiting key 12 made up of a plurality of contacts each arranged to short circuit only a portion of the total coil 6 in order to reduce sparking at the contacts. The coil 6 may also be shunted by a resistance without reducing the antenna input when key 12 is open, although this resistance is not necessary under normal circumstances except in high power arcs. Reference character 14 shows a balance resistance absorbing the equivalent of the energy input to the antenna when inserted in the primary circuit by opening 10 of its shunting key or plurality of keys 15. The primary circuit is grounded at 16.

The sparking at the contacts of key 12 across the turns of the primary coupling coil 6 may be reduced to negligible value by 20 connecting the key in shunt with the secondary coupling coil 7 as indicated by reference character 18 in Fig. 2. One side of each of the sets of keys 15 and 18 is always at ground potential in this circuit and, therefore, safe 25 to touch during keying. A variometer 19 is connected in the antenna circuit for adjusting the frequency of the circuit in fine degrees. The electromagnets which control the keys 15 and 18 are so connected that 30 keys 15 open when keys 18 close, and vice versa.

The circuits described herein are the result of extensive investigations with high power arc transmitters. The circuits have 35 been found to be particularly adapted to high power arc transmitters due to the exact balance of power obtainable between signal and no signal positions. This uni-wave system permits as steady operation of 40 the arc as the existing double wave or compensation systems. It is not necessary that keys 15 and 18 overlap with any degree of precision, for with the present circuits the arc is steady even under the condition of much power unbalance. Keys 15 and 18 45 may be combined in one key or may be two separate units as represented in the drawings.

Five functions are performed by keys 15 and 18 as follows:

Key	Signal position	No signal position
15	Cuts out of circuit balancing resistance 14.	Balances power input by cutting in antenna balancing resistance 14.
15 18	Shortens wave of primary. Applies driving voltage to antenna.	Lengthens wave of primary. Removes driving voltage from antenna.
18	Tunes antenna to wave of primary.	Shortens wave of antenna.
18	Provides maximum coupling to antenna.	Provides minimum coupling to antenna.

Fig. 3 shows a method of eliminating inherent coupling which may exist between the primary and secondary circuits.

It is desirable to mount the primary inductance 5 at right angles with the loading

inductance 9, but this may not be practicable. In order to avoid inherent coupling I may provide an inductance 24 which is placed in series with resistance 25 and shunted by key 26 in the primary circuit. The inductance 24 is of such value as to throw the primary and secondary circuits out of resonance by changing reactance upon operation of key 26. The reactance change when keying becomes sufficiently great that leakage into the antenna is prevented. By use of this additional inductance 24 the antenna circuit is less likely to have any residual currents therein between signals.

While the coupled circuit eliminates undesired harmonics to a considerable degree, I may provide a double by-pass circuit, as represented in Fig. 4, to more completely eliminate from the antenna system all frequencies except the working wave. The by-pass circuits are indicated at 27 and 28 comprising low reactance paths for harmonics, and high reactance paths for the fundamental or working wave. The paths include inductance 29 and capacities 30 and 31, ammeters 32 and 33 being placed in each of the by-pass circuits to determine the relative conditions thereof.

The ammeter 23 indicates the total current in the primary oscillating circuit, while the ammeters 32 and 33 indicate the current in the circuits having low reactance for harmonics. In a series of observations this circuit arrangement has been found extremely effective in eliminating the radiation of harmonics.

Fig. 5 is an audibility chart prepared by taking observations at a distance of 2.6 miles from the arc transmitter, employing a two wire antenna and two stages of audio frequency amplification. The working wave audibility is indicated by the vertical curve 34. The only harmonic to be observed after searching over the range indicated by the abscissae was one of extremely slight audibility indicated at 35. In other arc signaling circuits harmonics exist at frequent intervals throughout the range indicated and cause considerable interference around the broadcasting range.

The theory of operation of the invention is as follows:—In the signal position Fig. 1, key 12 is open and 15 is closed. The antenna is energized by transfer of energy from the primary circuit to the secondary circuit by means of coupling coils 6 and 7. The wave lengths of the primary and secondary circuits are equal and a maximum of energy flows to the antenna. In the non-signal position key 12 is closed. The antenna energy drops to zero due to the fact that the antenna driving voltage has been reduced to zero by short circuiting the coupling coil 6 and to the additional fact that the primary circuit wave has been shortened

by the removal of the inductance of the primary 6 of the coupler. Key 15 inserts the power balancing resistance 14 in the primary circuit, keeping the arc flame steady.

5 Where the secondary coupling coil 7 is shunted by keys 18 as in Fig. 2, the operation is the same except that sparking at the key contacts becomes negligible, and by reason of the fact that one side of both sets of keys is at ground potential they are safe to touch during keying.

10 The operation of the circuit diagrams in Figs. 3 and 4 is similar to the circuits heretofore described. Contrary to expectations, the coupled arc is not the same as the well known coupled spark circuit. In spark sets a relatively small inductance and large capacity is required for the circuits, whereas in coupling the arc with the antenna inductively by removing the usual conductive connection with the antenna the circuits require a 20 relatively large inductance.

15 By my arrangement of coupled circuit, keying system, and double by-pass circuits, the arc becomes as efficient a form of transmitter—other things considered—as can be desired when compared to other forms of transmitters available for radio signaling.

20 While I have described my invention in certain specific embodiments and with particular reference to an arc generator of sustained oscillations, it is to be understood that modifications may be made within the scope of the appended claims without departing from the spirit of my invention.

25 Having thus described my invention, what I claim and desire to secure by Letters Patent of the United States is as follows:

30 1. A radio transmitting system, comprising in combination an antenna system, means for generating sustained oscillations, a primary oscillating circuit connected with said means, a primary coupling coil connected in said circuit, a secondary coupling coil connected with said antenna system and inductively coupled with said primary coupling coil, and a plurality of sets of signaling keys, one of said sets of keys being connected in shunt with said primary coupling coil and another of said sets of keys being connected in series with said primary oscillating circuit and in parallel with a resistance arranged to absorb the energy normally radiated by said antenna system when said keys in shunt with said resistance are opened.

35 2. A radio transmitting system, comprising in combination an antenna system, means for generating sustained oscillations, a primary oscillating circuit connected with said means, a primary coupling coil connected in said circuit, a secondary coupling coil connected with said antenna system and inductively coupled with said primary cou-

pling coil, and a plurality of sets of signaling keys, one of said sets of keys being connected in shunt with the primary coupling coil, and another of said sets of keys being connected in series with said primary oscillating circuit and in parallel with resistance. 65

3. A radio transmitting system comprising in combination an antenna system, means for generating sustained oscillations, a primary oscillating circuit connected with said means, a primary coupling coil connected in said circuit, a secondary coupling coil connected with said antenna system and inductively coupled with said primary coupling coil forming a coupled system, and a plurality of sets of signaling keys, one of 70 said sets of signaling keys being connected in shunt with the primary coupling coil and the other of said sets of signaling keys being connected in shunt with an absorbing resistance and in series with said primary oscillating circuit, said signaling keys being arranged so that one set is open while the other set is closed for transmitting a signal whereby energy is radiated by said antenna 75 only during signaling intervals. 80

4. In a high frequency electric circuit, the combination of a source of power, a resonant circuit coupled thereto; said resonant circuit including an inductance, a coupling coil and a resistance in series with each other; and means for alternately rendering the coupling coil and the resistance inoperative, said means consisting of a single multicontact key, said key consisting of a plurality of pairs of contacts, one pair of contacts connected to the terminals of the resistance, another pair of contacts connected to the terminals of the coupling coil and means for alternately opening and closing each pair of contacts. 90

5. In a high frequency electric circuit, the combination of a source of power, a resonant circuit coupled thereto; said resonant circuit including an inductance, a coupling coil and a resistance in series with each other; and means for alternately rendering the coupling coil and the resistance inoperative, said means consisting of a single multicontact key, said key consisting of a plurality of pairs of contacts, one pair of contacts connected to the terminals of the resistance, another pair of contacts connected to the terminals of the coupling coil and means for alternately opening and closing each pair of contacts, said means consisting of a lever 100

105 pivoted about a point centrally disposed with respect to the pairs of contacts, a plurality of conducting members mounted upon the lever and arranged to alternately close the pairs of contacts as the lever is moved about its pivot. 110
